(57) CLAIM

The ornamental design for a combined test unit and package for saliva and other fluids, as shown and described.

DESCRIPTION

FIG. 1 is a front, top and left side perspective view of a combined test unit and package for saliva and other fluid, showing my new design;

FIG. 2 is a rear, top and left side perspective thereof; FIG. 3 is a front top perspective view of a portion thereof in which the closure flap shown in the closed position at the upper right in FIG. 1 is shown in the open condition; and, FIG. 4 is a perspective view of the dipstick shown in FIG. 1, shown removed from the package.

FIG. 5 is a left-side elevational view of the dipstick portion of FIG. 4, the right-side elevational view thereof being a mirror image and, therefore, not shown.
